Primary Examiner — Melody N Brown(74) *Attorney, Agent, or Firm* — Dorsey & Whitney LLP(57) **CLAIM**

The ornamental design for an car, toy replicas and/or other replicas, as shown and described.

DESCRIPTION

FIG. 1 is a front perspective view of an car, toy replicas and/or other replicas showing my design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a top plan view thereof.

The broken lines represent portions of the car, toy replicas and/or other replicas that form no part of the claimed design.
